UNITED STATES PATENT OFFICE.

JOSEPH A. READ, OF PHILADELPHIA, PA., ASSIGNOR TO GILBERT COMBS
AND JOHN BAWDEN, BOTH OF FREEHOLD, N. J.

DESIGN FOR A FIRE-PLACE-LINING PLATE.

SPECIFICATION forming part of Design No. 12,871, dated April 11, 1882.

Application filed March 6, 1882. Term of patent 7 years.

To all whom it may concern:

Be it known that I, JOSEPH A. READ, a citizen of the United States, and a resident of Philadelphia, Pennsylvania, have invented or
5 produced a new and original Design for a Fire-Place-Lining Plate, of which the following is a specification.

My design is fully shown in the accompanying photographic illustration, which shows one
10 of the plates. Each plate comprises a number of small rectangular panels, the latter having ornamental borders and central medallions comprising representations of animals, these
15 medallions constituting the main feature of the design.

I claim—

1. The design for a plate for fire-place linings, said design comprising a series of panels with medallions representing animals, all substantially as described and shown. 20

2. The design for a plate for fire-place linings, said design comprising a series of panels with ornamental borders and central medallions representing animals, as shown and described. 25

In testimony whereof I have signed my name to this specification in the presence of two subscribing witnesses.

JOSEPH A. READ.
